LOCK STRIKE

Howard McNeill, Philadelphia, Pa.

Application March 8, 1934, Serial No. 714,620

6 Claims. (Cl. 70—52)

This invention relates to door operating mechanism; and it has reference more particularly to mechanism for operating the doors of automobiles and the like.

Considered from the broadest viewpoint, my invention is directed toward the provision of a simple and reliable key-lock controlled mechanism for operating doors, that is to say: to mechanism capable of effecting automatic opening of doors upon release of the keeper by a lock switch.

An object of my invention is to provide, in a door operating mechanism having the above attributes, means in association with the lock switch whereby the keeper release may be effected mechanically in the event of failure of the electric current or derangement of the electric means.

In connection with door operating mechanism for automobiles it is a further aim of my invention to dispense with the necessity for external door operating handles, thereby eliminating objectionable lateral projections on the car bodies, and minimizing wind resistance.

Another object of my invention in connection with electrically-actuated door operating mechanism for automobiles is to afford means, whereby, when the ignition is turned on, the circuit of the mechanism is automatically broken, to the end that the doors cannot be opened from the outside except mechanically with the aid of the lock key. Thus, on the one hand, the car may be parked, with the engine running, safe against theft; while on the other hand, the doors are secure against being opened from without by anyone jumping on the running board while the car is in motion, the doors being always operable from within however by the usual door bolt actuating handles at the interior.

My invention is also directed in part toward the provision of an electro-mechanical mechanism whereby a number of automobile or other doors may be selectively operated under control of a single lock switch.

Still other objects and attendant advantages of this invention will be manifest from the detailed description following of the attached drawings, wherein Fig. I is a fragmentary horizontal sectional view of an automobile car body at one of the door openings, showing a single unit of my improved door operating mechanism incorporating spring actuated impellers for swinging the door to open position upon keeper release.

Fig. II is a front view of the door operating unit

removed, with the left hand portion in section for purposes of clarity.

Fig. IIa is a detail section taken on the plane designated by the arrows IIa—IIa in Fig. I.

Fig. III is a vertical sectional view taken as indicated by the arrows III—III in Fig. I.

Fig. IV is a view corresponding to Fig. I showing the keeper of the unit retracted and the door partly open.

Fig. V is a fragmentary sectional view taken as indicated by the arrows V—V in Fig. I, with the switch means of the unit in locked position, and showing diagrammatically the electrical connections embodied in the mechanism.

Figs. VI, VII and VIII are views corresponding to Fig. V showing the switch means in different positions incident to electrical and mechanical operation of the unit.

Fig. IX is a view like Fig. I showing my invention embodied in a double unit enabling selective actuation of the front and rear doors at one side of an automobile.

Fig. X shows a front view of the double unit removed from the car body.

Fig. XI is a fragmentary sectional view taken as indicated by the arrows XI—XI in Fig. IX and showing the control switch means of the double unit in locked position.

Figs. XII, XIII, XIV, XV and XVI are views corresponding to Fig. XI showing the lock switch means in different positions incident to electrical and mechanical operation of the double unit.

Fig. XVII is a view corresponding to Fig. I showing an alternative form of single unit.

Fig. XVIII is a front elevation of the single unit shown in Fig. XVII.

Fig. XIX is a plan sectional view taken as indicated by the arrows XIX—XIX in Fig. XX.

Fig. XX is a vertical sectional view taken as indicated by the arrows, XX—XX in Fig. XVII.

Fig. XXI is a fragmentary detail sectional view taken as indicated by the arrows XXI—XXI in Fig. XVII and showing the switch means of the unit in locked position.

Figs. XXII, XXIII and XXIV are views corresponding to Fig. XXI showing the switch means in different positions incident to electrical and mechanical operation of the unit.

With more detailed reference first to Figs. I—VIII of these drawings, the numeral 1 (Figs. I, III and IV) designates the hollow side wall of a metallic automobile body whereof the outside sheet is recessed as at 2 along one of the vertical edges of the door opening 3, to accommodate the lap flange portion 4 of the vertical

swinging edge of the door 5. As illustrated the door 5 is of the usual hollow sheet metal construction and provided with a bevel-ended latch bolt 6 capable of being actuated by a suitable turn handle (not shown) from the interior of the automobile. However, in accordance with my invention, the usual exterior operating handle is omitted from the door. The single type door operating unit featured in this embodiment of my invention comprises a centrally-open box-like housing 7 which is set into the hollow of the wall at the vertical edge of the door opening 3, and secured by a number of screws 8. Swingable about a vertical arbor 9 within the housing 7 is a keeper 10 which, as is usual in automobile practice, has keeper and safety projections 11 and 12 to cooperate with the latch bolt 6 in the door 5. A helical spring 13 surrounding the arbor 9 and having one end thereof anchored in the housing 7 at 14 and the other end 15 bearing against the keeper 10, serves to yieldingly maintain the latter in the active position shown in Fig. I. Normally with the door 5 closed, the keeper 10 is positively held against movement by a holding means in the form of a detent 16 which is swingable about another vertical arbor 17 within the housing 7, and formed with a tooth end 18 to engage the notch 19 in a rearward extension or lug 20 of said keeper. A pair of coiled springs 21 surrounding the arbor 17 urge the detent 16 toward the keeper 10. From Figs. I and IV it will be noted that the detent 16 has an angularly directed tail 22 whereof the terminal tip 23 is beveled as indicated by the shading, and reaches into a cut-out 24 in the inner vertical wall 25 of the housing 7.

Carried by the keeper 10 is an electromagnetic device or magnet 26 whereof the pole end 27 lies adjacent the tail 22 of the detent 16 when the parts are in the normal position as in Fig. I. At its inner end, the magnet 26 is secured by means of a screw to an angle piece 28, which latter is secured in turn by screws to the pivot ears 29 of the keeper 10. For greater security, the magnet 26 is embraced by a clamp band 30 which is made fast to the rearward extension 20 of the keeper 10 likewise by screws.

Suitably fitted into the wall 1 of the automobile body adjacent the door opening 3 is a cylinder lock 31 which, insofar as its internal construction is concerned, may be of the conventional type customarily employed in automobiles; that is to say, it includes a securing sleeve 31g having a longitudinal slot 31h with which the tumblers 31i normally coat for locking purposes. However, in accordance with my invention, the barrel 32 of the cylinder lock 31 is provided with a flat diametral finger grasp 33 which is longitudinally disposed with respect to the key receiving slot 34; while the securing sleeve 31g aforesaid is provided with an auxiliary tumbler receiving cut-out 31j—Fig. II—for a purpose later on explained. As shown, the inner end of the lock barrel 32 is afforded journal support in an apertured bearing projection 35 on the housing 7, and provided with an axial shaft extension 36 which passes through the inside 37 of the wall 1 and terminates in a flat finger grasp 38, similar to the grasp 33, accessible at the interior of the automobile body. The shaft extension 36 of the lock barrel 32, it will be further observed, has two contiguously allocated radial fingers 39 and 40 which are spaced by an angle of 45°, and adapted to move through the opening 24 in the frontal wall 25 of the housing 7. The end of

the finger 39 is bevelled, as at 41, for camming action with the bevelled tip 23 on the tail 22 of the detent 16. The other finger 40 constitutes a switch, the same being adapted to engage a spring contact 42, which, with interposition of insulating washers 43, is secured by a screw 44 to the wall 25 of the housing 7 and electrically connected by a flexible conductor 45 with the magnet 26, see Figs. I, IV and V.

Above and below its open central portion, the housing 7 has integrally formed hollow bosses 46 for the guidance of spring pressed impeller plungers 47 which are relied upon to automatically swing the door 5 open upon release of the keeper 10. The forward end portions 48 of these 15 plungers 47 are square in cross section (see Figs. II and III), and fit the correspondingly configured frontal portions 49 of the cavities in the bosses 46. The rear portions of the boss cavities are cylindric as indicated at 50; and the square 20 portions 48 of the plungers have their corners rounded part way of their lengths as at 51 for capacity to move into the cylindric portions of the boss hollows. As further shown in Fig. III, the inner ends of the plungers 47 are diametrical- 25 ly reduced and cylindric as at 52, and surrounded by stout helical compression springs 53. One end 54 of each compression spring 53 is anchored in a hole in the rear wall of the corresponding hollow boss, while the other end 55 engages a 30 circumferential notch in the corresponding plunger. Upon release of the door 5, the springs 53 thrust the plungers 47 forward in the guide bosses 46, the movement being limited by engagement of the ends 55 of the springs with 35 the circumferential shoulders 56 within the cavities of said bosses. At their rear ends, the impeller plungers 47 are formed with axial tips 57 of smaller diameter, which, when the plungers 57 are fully depressed, engage guide apertures 58 in 40 the back ends of the bosses 46. It is to be noted from Fig. III that the bosses 46 are cut away as at 59 to enable introduction of the springs 53 into the boss cavities incident to assembling of the unit, whereupon the impeller plungers 47 are inserted into said bosses from the front and the ends 55 of the springs snapped into the circumferential notches of said plungers.

In addition to the function above mentioned, the plungers 47 assist in the vertical support of 50 the swinging edge of the door 5, and in this latter function they cooperate respectively with pairs of spaced anti-friction rollers 60 within recesses 61 of a plate 62 which is set into the swinging edge of the door and secured by screws 63 as 55 shown in Fig. III. A rubber buffer 64 anchored in the plate 62 at its center absorbs shocks attendant upon closing the door.

Referring now to Fig. V which shows the wiring diagram for the door operating mechanism, the 60 magnet 26 is connected by a conductor 65 to one pole of a battery 66 which may be the ignition and lighting battery of the automobile. Connected with the other pole of the battery 66, by another conductor 67, is a fixed spring contact 68 which may be like the contact 42. This spring contact 68 is adapted to be engaged by a finger 69 projecting radially from the barrel of the "ignition lock" of the automobile, which lock is conventionally indicated at 70. It is to be understood that all the parts of the mechanism except the spring contacts 42 and 68 are grounded through the body and frame of the automobile; and furthermore, that in Figs. I, II, III and V, the parts are all in the positions which they oc- 75

cupy when the automobile is parked and locked, with the ignition switch 70 (Fig. V) turned off.

Assuming that the barrel 32 of the cylinder lock 31 occupies a position shown in Fig. II, with the key slot 34 horizontal, when the door 5 is both electrically and mechanically locked, the operation of the form of my invention just described is as follows:

The key is inserted into the slot 34 of the cylinder lock 31, and passed through the consecutive relatively-staggered openings in the tumblers 31*i* to withdraw the latter from engagement in the locking slot 31*h*, whereupon the barrel 32 of said lock is turned counterclockwise through a quadrant, or an angle of 90°, from the position shown in Figs. I, II and V, to that shown in Fig. VII, in which position the barrel is yieldingly maintained thereafter by a bow spring 31*k* supported by pins 31*l* on the housing apertured bearing projection 35 being engaged by circumferentially-spaced studs 32*g* at the inner end of the barrel aforesaid, in an obvious manner, and as will be better understood from Fig. II*a*, more particularly. In passing from the position of Fig. V, through that shown by Fig. VI, to the position of Fig. VII, when the key slot 34 is in a vertical position, with the tumblers 31*i* engaged in the auxiliary cut-out 31*j* and in which position it remains while the car is occupied, the switch finger 40 on the lock barrel extension 36, wipes the contact 42, thereby closing the circuit through the magnet 26, the attendant movement of the trip finger 39 being an idle one. As a consequence of the energization of the magnet 26, the holding detent 16 is attracted and rocks clockwise on the pivot 17, with attendant withdrawal of its toothed end 18 from the notch 19 in the keeper 10. Thereupon, the impeller plungers 47 are forcibly thrust forward by the springs 53 in the bosses 46 of the housing 7, thereby reacting against the plate 62, incidentally overcoming the weaker spring 13 of the keeper 10 and moving the latter aside after the manner illustrated in Fig. IV, and swinging the door 5 to open position. Upon clearance of the latch bolt 6 in the door 5, the keeper 10 is temporarily maintained in its retracted position against the action of its spring 13 by coaction of the sloping back of the tooth 18 of the detent 16 with the safety projection 12 of said keeper as in Fig. IV. In stepping into the car the driver closes the door 5 in the usual manner by drawing upon the handle (not shown) at the inside incident to which the latch bolt 6 in striking the keeper 10 causes the latter to be swung back to its normal position with the detent 16 engaging the notch 19 as in Fig. I. During turning of the ignition control 70 to the "on" position indicated in dot-and-dash lines in Fig. V, the circuit through the magnet 26 is broken due to passing of the finger 69 from the contact 68, thereby making it impossible for the door to be opened from the outside by an unauthorized person jumping on the running board while the car is in motion. It also makes impossible opening of the door by accidental actuation of the switch finger grasp 38 within the automobile, and thus affords the occupants greater safety while the vehicle is in motion. Upon turning "off" the ignition, the electric circuit of the door operating mechanism is re-established so that the door 5 can be electrically opened from within by turning the finger grasp 38 clockwise from the position of Fig. VII to that of Fig. V. In leaving the automobile, the door 5 is closed by slamming it with sufficient force to overcome the springs 53 of the impeller

plungers 47, the latch bolt 6 incidentally engaging the innermost projection 10*a* of the keeper 10 and causing the latter to be swung outward to the normal position of Fig. I with the assistance of its spring 13; while the detent 16 is thrust aside by the safety projection 12. To lock the car, the finger grasp 38 is turned clockwise through a quadrant from the vertical to horizontal position, or from the normal position of Fig. VI to that of Fig. V when the lock 31 will snap shut automatically in locked position, as will be clearly obvious from Fig. II more particularly, by the tumblers 31*i* riding out of the auxiliary cut-out 31*j* into the slot 31*h*. In the event of failure of the battery 66 or derangement of any part of the electric system, or when the car is parked with the engine running (during which time the electric circuit is interrupted as before explained), the door may be mechanically opened from the outside after insertion of the key into the lock, by clockwise turning of the lock barrel 32, through a quadrant from the position of Fig. V to the position of Fig. VIII. As this is done, the bevel ended trip finger 39 on the lock barrel extension 36 wipes past the bevel tip 23 on the tail 22 of the holding detent 16, with the result that the latter is withdrawn (as during electrical operation thereof) to release the keeper 10 and permit automatic opening of the door 5 under the thrust of the spring-pressed impeller plungers 47. 30

In Figs. IX-XVI, I have shown my invention embodied in a double unit capable of serving in common for the two doors 5*d* and 5*e* at the side of an automobile. As illustrated, the housing 7*d* of the double latch unit occupies the hollow of the vertical center or dividing post 90 of the automobile body between the doors 5*d* and 5*e* whereof the swinging edges close against said post 90. The latch unit in this case includes keepers 10*d* and 10*e* to cooperate respectively with the bolts 6*d* and 6*e* of the doors 5*d* and 5*e*, said keepers being pivoted on arbors 9*d* and 9*e* fixed within the hollow of the casing 7*d* near opposite ends of the latter. As shown, the keepers 10*d* and 10*e* are maintained yieldingly in the position illustrated in engagement with the door bolts 6*d* and 6*e* by means of the torsion springs 13*d* and 13*e* respectively. The associated holding detents 16*d* and 16*e* are pivoted on arbors 17*d* and 17*e* and subject to springs 21*d* and 21*e* but here engage the backs of the keepers 10*d* and 10*e*. The magnets 26*d* and 26*e* which respectively actuate the detents 16*d* and 16*e* are in this instance fixedly secured to the back wall of the housing 7*d* with their pole faces 27*d* and 27*e* disposed adjacent 55 the tails 22*d* and 22*e* of said detents. As further shown, the rearward extension 36*d* on the barrel 32*d* of the lock 31*d* of the double unit has a radial trip finger 39*d* with a bevelled end to cooperate with the counter-bevelled tip of the detent 16*d*, and a pair of diametrically opposite radial switch fingers 40*d* and 40*e* angularly spaced from the finger 39*d*. The switch fingers 40*d* and 40*e* are adapted to cooperate respectively with spring contacts 42*d* and 42*e*, which latter are secured, with interposition of insulation, to the frontal wall of the housing 7*d* by means of screws. As shown, the flexible leads 45*d* and 45*e* of the magnets 26*d* and 26*e* are respectively connected to the spring contacts 42*d* and 42*e*, Figs. XI-XVI. All other electrical features are intended to be similar to those illustrated in Fig. V. Moreover, in all other respects the modification of Fig. IX is similar to the first described embodiment of my invention. Therefore, in order to avoid the 75

necessity for repetitive description, all corresponding parts have here been identified with the same reference numerals heretofore employed but with the addition of the letter *d* in each case 5 for the purposes of distinction.

The operation of this double latch form of my invention is as follows:—To open the front door 5*d*, the key is inserted into the lock 31*d* and the latter given a quarter turn counter-clockwise from the normal locked position of Fig. XI to the position of Fig. XII incident to which the finger 40*d* wipes contact 42*d* with resultant energization of the magnet 26*d*, withdrawal of the keeper 10*d* and release of the door 5*d* to 10 the action of the impeller plungers 47*d*. If the rear door 5*e* is to be opened the lock barrel 32*d* is turned further in the counter-clockwise direction to the position shown in Fig. XIV so that the radial finger 40*d* engages with the spring 15 contact 42*e*, the magnet 26*e* being thereby energized, the detent 16*e* withdrawn, and the keeper 10*e* released to free the door 5*e* to the action 20 of the impellers 47*c*. In the event that the electric system is disorganized for any reason, the 25 front door 5*d* may be mechanically released after insertion of the key into the lock 31*d* by turning the lock barrel 32*d* clockwise from the position of Fig. XI through the position of Fig. XV to that shown in Fig. XVI incident to which the 30 bevel-ended trip finger 39*d* will wipe past the bevel tip 23*d* of the tail 22*d* of the detent 16*d* and cause retraction of the latter from the latch member 10*d*. When the parts are in the positions 35 illustrated in Figs. IX, X and XI, it will be observed that the fingers 40*d* and 40*e* lie between the tails 22*d* and 22*e* of the detents 16*d*, 16*e* and the pole faces 27*d* and 27*e* of the magnets 26*d* and 26*e*, thereby functioning as a positive 40 means to prevent unauthorized electrical or mechanical operation of the doors. Thus with the last described form of my invention two doors may be selectively operated with a single lock controlled switch.

In the alternative single latch unit embodiment 45 of my invention illustrated in Figs. XVII-XXIV, a solenoid 26*f* is utilized instead of a magnet. The solenoid 26*f* is however secured to the pivoted keeper 10*f* by means of a band or strap 30*f* after the manner described in connection with 50 the attachment of the magnet 26 in Fig. I. As shown, the armature 27*f* is guided in insulate 55 tubular core piece 91 of the solenoir, the upper portion of the said armature being of hard rubber or the like and having a head 92 which is acted upon by the torsion spring 13*f*. Accordingly, the armature 27*f* normally occupies the 60 position shown in Fig. XVII with its end projecting and engaging the edge 93 of an opening in the frontal wall of the housing 7*f* to hold 65 the latch member 10*f* locked in active position. The cylinder lock 31*f* is in this case mounted in the door 5*f*. When the door is in its closed position, the axial extension 36*f* of the lock barrel reaches through a sectoral aperture 94 in the 70 outside sheet of the automobile body adjacent the door opening 3*f*. As shown, the lock barrel extension 36*f* is provided with a single switch finger 39*f* which is adapted to cooperate with the spring contact 42*f*, and which has its end beveled as at 75 23*f* for capacity to cooperate as well with the solenoid armature 27*f*, whereof the end is counter beveled as at 95. In this instance but a single impeller plunger 47*f* is employed, the same being arranged to engage between rollers 60*f* in the recesses 61*f* of a plate 62*f* which is set into the

lap flange 4*f* along the door edge. The plate 62*f* also provides bearing for the barrel 32*f* of the lock 31*f*. The impeller plunger 47*f* is here of slightly different construction, it being formed with an enlarged head 96 which has an axial 10 recess 97 capable of wholly accommodating the spring 53*f* when the latter is compressed as in Fig. XV. From Fig. XIX it will be observed that the plunger head 96 has a notch 98 in its rear face to cooperate with an upwardly projecting 15 half round lug 99 on the keeper 10*f* for a purpose to be presently described. To open the door 5*f*, the key is inserted into the slot of the lock 31*f* and the barrel 32*f* turned counterclockwise through a quadrant with the result that the 20 switch finger 39*f* is moved from the position shown in Fig. XXI to that shown in Fig. XXII, in which latter position said finger is yieldingly held by the spring (not shown) of the lock. A slightly further movement of the lock barrel 32*f*, 25 either with the key or by means of the finger grasp 33*f*, beyond the position of Fig. XXII, will cause the finger 39*f* to engage the spring contact 42*f* as in Fig. XXIII, with attendant energization of the solenoid 26*f* and retraction of 30 its armature 27*f*. As a consequence the projecting end of the armature 27*f* is disengaged from the edge 93 of the frontal opening of the housing 7*f*, whereupon the impeller 47*f* immediately 35 becomes operative to swing the door to open position as in the previous embodiments of my invention. Incident to closing the door 5*f* subsequently, the hemispherical lug 99 on the keeper 10*f* is engaged by the rear end of the impeller plunger 47*f* in a manner which will be obvious 40 from Fig. XIX and thereby positively returned to its active position with the solenoid armature 27*f* projected and engaging the edge 93 as in Fig. XVII. In the event of failure of the electric current, the door 5*f* may be opened by turning 45 the lock barrel 32*f* counterclockwise beyond the position of Fig. XXIII to that shown in dot-and-dash lines in Fig. XXIV when the beveled end of the switch finger 39*f* will wipe past the bevel end of the armature solenoid, causing the latter 50 to be thrust inward to clear the edge 93 for release of the keeper 10*f* as in electric operation. The single finger 39*f* on the extension 36*f* of the lock barrel 32*f* thus performs the function of both a switch and a mechanical means for effecting the release of the door.

While in the several illustrated forms of my invention I have shown the door impelling means as incorporated with the housings of the keeper units, they may, if found convenient or desirable 55 in practice, be made as separate devices and mounted either in the automobile bodies, or in the doors.

It is thought to be clear from the foregoing without the necessity for further illustration, that 60 my invention is adaptable for the operation of doors other than those of automobiles as pointed out in the introductory portion of the specification. Accordingly, the broader of the appended claims are to be construed with the above thought 65 in mind.

Having thus described my invention, I claim:

1. In door operating mechanism, a spring-urged keeper adapted to engage a projection on the door; a pivotal spring-urged holding member having a portion adapted to positively hold the keeper normally in active position and the other portion providing a tail; an electromagnetic device carried by the keeper with its pole proximate the holding member tail for actuating said 75

member; and a manually operable switch whereby an electric circuit may be closed through the electromagnetic device to effect withdrawal of the holding member aforesaid.

5. 2. In door operating mechanism, a spring-urged keeper adapted to engage a projection on the door; a member to positively hold the keeper normally in active position; an electromagnetic device carried by the keeper and adapted to 10 actuate the holding member; and a manually operable switch whereby an electric circuit may be closed through the electromagnetic device to effect withdrawal of the holding member aforesaid.

15. 3. In door operating mechanism, a spring-urged keeper adapted to engage a projection on the door; a member to positively hold the keeper normally in active position; an electromagnet carried by the keeper with its pole face normally 20 contiguous to the holding member; and a manually operable switch whereby an electric circuit may be closed through the magnet to effect withdrawal of the holding member.

4. A door operating mechanism comprising an 25 open box-like housing; a spring-urged keeper in said housing adapted to engage a projection on the door; a member to positively hold the keeper normally in active position; an electromagnetic trip means carried by the keeper with its pole

face contiguous to the holding member; and a cylinder lock journaled in the housing with a radial finger on its barrel adapted to wipe a fixed contact in a circuit through the electromagnetic trip means to effect release of the holding 5 member.

5. In door operating mechanism, a vertically-pivoted spring-urged member having keeper and safety projections adapted to engage a latch bolt on the door; a spring urged vertically-pivoted 10 detent embodying a toothed portion, for engagement in a notch in the keeper member to positively hold the same normally in active position, and a reversely-directed angular tail portion; an electro-magnet carried by the keeper with its 15 pole face normally contiguous the detent tail portion; and a cylinder lock having an axial extension with a radial finger, which finger serves to wipe a stationary contact for closing a circuit through the magnet to effect electric release of 20 the holding detent.

6. The combination of claim 5 wherein the detent toothed portion not only coacts with the keeper member notch for holding said keeper normally in active position, but also serves to 25 engage the keeper safety projection for temporarily holding said keeper in inactive position.

HOWARD McNEILL.
